FRANS OSCAR CARLSON, OF NEW YORK, N. Y.

GAS-BURNER.

No. 820,623.

Specification of Letters Patent.

Patented May 15, 1906.

Application filed July 15, 1905. Serial No. 269,758.

To all whom it may concern:

Be it known that I, FRANS OSCAR CARLSON, a subject of the King of Sweden and Norway, residing in the borough of Brooklyn, city of 5 New York, in the county of Kings and State of New York, have invented certain new and useful Improvements in Gas - Burners, of which the following, taken in connection with the accompanying drawings, is a full, clear, 10 and exact specification.

My present improvements have relation chiefly to gas-burners intended for illuminating purposes; but obviously my invention may be advantageously applied in connection 15 with gas-burners for other purposes—such, for instance, as heating purposes.

The principal object of my invention is to provide or produce a gas-burner of few and simple parts, easy of construction and operation, 20 and reliable in action, which shall automatically prevent the flow of gas through the burner after the pressure has for any purpose been cut off or reduced below a degree necessary for the ordinary support of combustion 25 at the burner-tip.

In the use of gas for illuminating and other purposes it frequently occurs that the gas-pressure is reduced in the supply-pipes, either by accident or design, to a degree sufficient 30 to permit the ready extinguishment of the flame, and it frequently occurs that the gas-cock near the burner is accidentally opened after it has been once closed to extinguish the flame. In these and other similar cases with 35 the ordinary forms of burners the gas issues from the burner-tip without being consumed and becomes dangerous to life and health and property, as is very well understood.

To obviate these disadvantages in the use 40 of gas-burners, to accomplish the object of my invention as above set forth, and to secure other and further advantages in the matters of construction and operation, my improvements involve certain new and useful 45 peculiarities of construction, relative arrangements or combinations of parts, and principles of operation, as will be herein first fully described and then pointed out in the claims.

50 In the accompanying drawings, forming part of this specification, I have shown at Figure 1 a vertical view, partly in section and partly in elevation, of a gas-burner with an ordinary illuminating-tip and having my improvements applied in connection therewith, 55 the gas-cock being shown as opened and the

parts in full lines in position to permit the flow of gas to the tip without interference, as when the gas is ignited. Fig. 2 is a horizontal section and partial plan view on a plane 60 through line 2 2 of Fig. 1.

In both these figures like letters of reference wherever they occur indicate corresponding parts.

A is the shell of the burner, and B an ordinary illuminating-tip at the point where the gas is intended to be consumed. The shell A is threaded upon a suitable burner-seat C, into which gas is admitted from a supply-pipe D, the flow of gas being controlled and 70 regulated at the location of the burner by any ordinary form of gas-cock, as at E, interposed between the gas-supply pipe and the burner.

75 Into the seat C, of whatever form or character it may be, I introduce a plug F, having an axial perforation through it for the passage of gas, the top of this plug being finished so as to form a seat for the safety-valve which I employ, having a recess in its upper part to 80 accommodate a projection on the lower part of said valve and operating as a guide for the stem of the valve. The upper part of the seat C for the burner-shell is cut away or reduced, as at a a, and provided with openings, 85 as b b, through which the gas may pass on its way to the burner-tip.

90 Within the upper neck of the seat C, I locate the safety-valve which I employ, the same being comparatively light and composed of a flat disk G, having a projection on its lower face, the said projection being fitted to easily enter the recess provided for it in the upper portion of the plug F and carrying a slender stem d, which projects down through 95 the central perforation in the said plug. The stem d is not large enough to interfere with the necessary free flow of gas through the central perforation in the plug F. The valve and its appendages are of weight sufficient to 100 drop easily upon the plug F when the gas-pressure is sufficiently reduced or entirely cut off, and they are so calculated as to size and weight that the valve will be sustained in elevated position by the pressure of the outgoing gas on its under side after the valve 105 has been properly raised. Above the opening b b the burner-seat C is closed by a plug e, having a small perforation through it, the plug e being located so that the disk G in its 110 elevated position will rest above the openings b b.

As long as the valve G is maintained in its elevated position the gas may flow freely to the burner-tip. As soon as the pressure of gas is stopped or sufficiently reduced, either 5 by turning the gas-cock E or by any other means, the valve G will automatically drop and effectually close the passage for gas through the plug F. Then if the gas-cock G be opened or the pressure of gas in the supply- 10 pipe be restored the valve G will prevent the passage of gas to and through the burner-shell, thus operating as a safety appliance to automatically prevent the disadvantages heretofore pointed out. When the safety- 15 valve is opened, its whole lower surface is exposed to the pressure of the gas then flowing; but when it is seated or closed the gas-pressure can only act on an extremely-limited surface of the valve, and therefore cannot 20 raise or open it.

In order to open the valve G after it has been seated, suitable means are provided by which the valve may be purposely and manually raised from the exterior. H is a small 25 plug on the inner end of the stem f, passing down through an opening in the bottom of the burner-seat C and supplied with a small weight on its outer extremity, as at g. The stem f, with its plug H, are so seated that 30 they may be easily moved, but so that they will prevent escape of gas around them. After the gas has been turned on the ball or weight g is to be elevated by the hand or finger and then allowed to drop. The plug H, contacting 35 with the lower end of the stem d on the valve, raises the disk G above the openings b, and the pressure of the gas on the valve then holds it in opened position.

The stop-plug e has a small perforation 40 through it, as indicated, to permit the escape of gas which might leak around the circumference of the valve G. Otherwise there would be formed a chamber for this gas, and the gas expanding therein might under some 45 circumstances cause the seating of the valve by overbalancing the pressure on the under side of the valve.

The improvements being constructed and applied substantially in accordance with the 50 foregoing explanations, constitute a safety

appliance well calculated to answer all the purposes or objects of the invention hereinbefore alluded to.

Having now fully described my invention, what I claim as new herein, and desire to secure by Letters Patent, is—

1. In a gas-burner, the combination with the seat for the burner-shell, said seat having perforations and gas-channels, of a valve adapted and arranged to automatically close 60 the gas-channel in said seat when the gas-pressure is reduced, said valve being held open by the gas-pressure and provided with a projecting stem extending through the valve-seat, and a sliding rod for manually opening 65 the valve from the exterior, after it has been seated, by contacting directly with said projecting stem, substantially as set forth.

2. The combination with the seat for the burner-shell, said seat having perforations 70 and gas-channels, of the valve having a projecting stem, a seat for the valve, a sliding rod for manually opening said valve from the exterior by contacting directly with the said projecting stem, and a perforated stop located in the burner-seat above the uppermost position of the valve, substantially as and for the purposes set forth.

3. In a gas-burner, the combination with the automatically-closing valve located in the 80 burner, a seat for said valve, and a stop-plug for limiting the upward travel of the valve, said stop-plug being perforated to permit escape of gas, substantially as and for the purposes set forth.

4. In a gas-burner, the combination of the burner-shell, the seat therefor having perforations and gas-channels, an interior valve having a depending stem, a plug forming a seat for said valve, and means for manually 90 raising the valve from the exterior by contacting with the projecting valve-stem, substantially as and for the purposes set forth.

In testimony whereof I have signed my name to this specification in the presence of 95 two subscribing witnesses.

FRANS OSCAR CARLSON.
